(57) **CLAIM**

The ornamental design for a pill bottle with indicia and writing instrument holder, as shown.

DESCRIPTION

FIG. 1 is a perspective view of a pill bottle showing my new design.

FIG. 2 is a front perspective view of another embodiment thereof.

FIG. 3 is a bottom plan view of the pill bottle in FIG. 1.

FIG. 4 is a top plan view of the pill bottle in FIG. 1.

FIG. 5 is a top plan view of the pill bottle in FIG. 2.

FIG. 6 is a bottom plan view of the pill bottle in FIG. 2.

FIG. 7 is a left side elevation view of the pill bottle in FIG. 1.

FIG. 8 is a front elevation view of the pill bottle in FIG. 1.

FIG. 9 is a right side elevation view of the pill bottle in FIG. 1.

FIG. 10 is a rear elevation view of the pill bottle in FIG. 1.

FIG. 11 is a left side elevation view of the pill bottle in FIG. 2.

FIG. 12 is a front elevation view of the pill bottle in FIG. 2.

FIG. 13 is a right side elevation view of the pill bottle in FIG. 2; and,

FIG. 14 is a rear elevation view of the pill bottle in FIG. 2. The broken lines showing of the environment in the drawings is included for the purpose of illustrating only and forms no part of the claimed design.
